UNITED STATES PATENT OFFICE

FREDERICK W. ROETTGES, OF NEW YORK, N. Y., ASSIGNOR TO LIGHTING APPLIANCE COMPANY, INC., OF NEW YORK, N. Y.

DESIGN FOR A GLASS SHADE FOR A LIGHTING FIXTURE OR ARTICLE OF SIMILAR NATURE

Application filed May 28, 1930. Serial No. 35,826. Term of patent 3½ years.

To all whom it may concern:

Be it known that I, FREDERICK W. ROETTGES, a citizen of Germany, residing in New York, in the county of Kings and State of New York, have invented a new, original, and ornamental Design for a Glass Shade for a Lighting Fixture or Article of Similar Nature, of which the following is a specification, reference being had to the accompanying drawing, forming a part thereof.

Figure 1 is an elevational view of a glass shade for a lighting fixture, in which the por-

tions shown in plain outline involve more repeats of the portions shown completed in full lines.

Fig. 2 is a side elevational view thereof.

Fig. 3 is a top plan view thereof.

I claim:

The ornamental design for a glass shade for a lighting fixture, or article of similar nature, as shown and described.

In testimony whereof I affix my signature.

FREDERICK W. ROETTGES.
